UNITED STATES PATENT OFFICE.

ARTHUR PRACNA, OF EVERETT, WASHINGTON.

SWIVEL BAND-SAW GUIDE.

SPECIFICATION forming part of Letters Patent No. 770,105, dated September 13, 1904.

Application filed December 18, 1903. Serial No. 185,694. (No model.)

To all whom it may concern:

Be it known that I, ARTHUR PRACNA, a citizen of the United States, residing at Everett, in the county of Snohomish and State of Washington, have invented a new and useful Swivel Band-Saw Guide, of which the following is a specification.

The invention relates to improvements in upper guides for band-saw mills.

10 The object of the present invention is to improve the construction of upper guides for band-saw mills, and to provide a simple and comparatively inexpensive one adapted to be readily applied to a band-saw mill and capable of counteracting the tendency of a band-saw to deviate from or lead out of a straight line.

20 A further object of the invention is to provide a band-saw guide of this character capable of leading a band-saw before the same enters the material to be cut and whereby absolutely perfect lumber may be obtained.

25 Another object of the invention is to provide simple and efficient means for adjusting the band-saw guide and for positively holding the same at the desired adjustment.

30 The invention also has for its object to provide means for supporting and adjusting the band-saw guide which will not interfere with the arrangement of the guide close to the material to be cut and which will permit the guide to remain in close proximity to the material until the last piece of lumber is cut.

35 With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

40 In the drawings, Figure 1 is a perspective of a swivel upper band-saw guide constructed in accordance with this invention. Fig. 2 is a plan view of the same. Fig. 3 is a front elevation. Fig. 4 is a side elevation. Fig. 5 is

a vertical sectional view. Fig. 6 is a detail sectional view on the lines 6 6, Fig. 5.

Like numerals of reference designate corresponding parts in all the figures of the drawings.

55 1 designates the guide proper, which is constructed in the usual manner, being composed of two hinged sides or members, the outer one of which is provided with an integral upwardly-extending arm or column 2, which is 60 hung or suspended from a hanger or support 3. The hanger or support 3, which may be of any desired configuration, may be attached to a band-saw mill in any desired manner, and the means for connecting the hanger or support 65 with the band-saw mill may be varied to suit the character of the material to which the saw-guide is applied. In the accompanying drawings the hanger or support is connected with a pair of links 4, provided at their upper ends 70 with eyes for the reception of horizontal pivots 5 of a band-saw mill, (not shown,) and the lower ends of the links 4 are connected by pivot-bolts 6 or other suitable means with the hanger or support 3. The links 4 are adapted 75 to permit the band-saw guide to move longitudinally and vertically, whereby should the saw-guide be struck by a log it will rise and clear the same.

80 2 The upwardly-extending portion or arm of the band-saw guide is transversely curved at the top at 7 and is provided at its outer convex face with upper and lower curved flanges 8 and 9, L shape in cross-section, to provide a tongue and groove at the bottom of the said 85 flanges. The curved flanges are arranged in the arc of a circle the center of which is coincident with the center of the upright effective portion of the band-saw 10. The tongues depend from the curved flanges, as clearly shown 90 in Fig. 5, and they are received in corresponding ways of semicircular bearing-plates 11 and 12, which are concentric with the saw and which are provided with upwardly-extending tongues and grooves, located at the concave 95 faces of the bearing-plates and matching the tongues and grooves of the band-saw guide. The bearing-plates 11 and 12 are arranged in the arc of a circle the center of which coincides with the center of the saw, and they 100

have body portions approximately L shape in cross-section to fit the upper and lower edges and the inner face of the adjacent portion of the hanger or support 3. The transversely-5 curved portion of the hanger is provided at its top and bottom with vertically-disposed curved flanges 13 and 14, which receive the bearing-plates and to which the same are secured by bolts or screws 15 and 16. The upper 10 bolts or screws 15 also serve to secure a cap or top plate 17 to the upper bearing-plate, and this cap or top plate, which is approximately semicircular, extends over the upper end of the arm or column of the band-saw 15 guide to render the bearing dust-proof. By hanging the band-saw guide in this manner it is capable of a partial horizontal rotation and is adapted to lead the band-saw before the same enters the material to be cut, and it is 20 capable also of effectually preventing the saw from deviating or leading out of a straight line, whereby absolutely perfect lumber may be cut.

The upwardly-extending arm or portion of 25 the band-saw guide is provided at the center of the transversely-curved part 7 with a pair of outwardly-extending horizontal ears 18, located in an opening 19 of the curved portion of the hanger or support and adapted to oscillate horizontally therein. These ears receive a pivoted block 19^a, which is secured between the ears by a pair of vertical pivots 20, having threaded shanks, which are arranged in threaded openings of the ears and 30 which are provided with reduced squared outer portions adapted to receive a wrench. The inner ends of the pivots are tapered to provide cone-bearings, and the outer portion of the threaded shanks receive jam or locking 35 nuts 21, which prevent any accidental rotation of the pivots.

The pivoted block is provided with a centrally-threaded aperture 22, disposed horizontally and receiving the threaded end 23 of a 40 rod or shaft 24, which extends longitudinally of the hanger or support and which has its other end journaled on the same in a bearing 24^a. This end of the operating rod or shaft is provided with a suitable hand-wheel 25, arranged at the outer side of the bearing 24^a. A collar or flange 26 is arranged at the inner side of the bearing 24^a, and a set-screw 27 is mounted on the said bearing for engaging the operating rod or shaft, whereby the same 45 is positively held at any adjustment. When the operating rod or shaft is rotated, the upwardly-extending arm or portion will be turned horizontally in the bearings or ways of the hanger or support, and the block 19^a 50 will oscillate in the space between the projecting ears and maintain its opening in alignment with the operating rod or shaft, whereby the latter is prevented from being sprung or strained. Also the joint prevents any lia-

bility of the parts binding or otherwise interfering with the adjustment of the saw. 65

The hanger or support may be connected with suitable supporting-cables 28 and 29, as clearly illustrated in Fig. 1 of the drawings. Suitable eyes 30 and 31 are provided for an 70 attachment of the cables, which may be provided with counterbalancing-weights in the usual manner.

It will be seen that the swivel upper band-saw guide is capable of leading a band-saw 75 before the same enters the material to be cut and that it is adapted to positively counteract any tendency of the band-saw to deviate from a straight line and that by it absolutely perfect lumber may be obtained. It will also 80 be apparent that the band-saw guide is capable of a limited horizontal rotation on an axis or center coincident with the center of the band-saw and that simple and positive means are provided for adjusting the band-saw guide 85 and for securing the same at the desired adjustment. Furthermore, it will be clear that the means for supporting and adjusting the band-saw guide permit the latter to be arranged close to the log or other material and 90 to remain in such position until the last piece of lumber is sawed.

Having thus described my invention, what I claim as new, and desire to secure by Letters Patent, is—

1. An upper band-saw guide capable of a horizontal rotary movement on an axis or center coincident with the center of the guided portion of a band-saw, whereby it is adapted to lead the same before the saw enters the material to be cut, substantially as described. 100

2. In a device of the class described, the combination of a hanger or support having upper and lower semicircular bearings concentric with the saw, and an upper band-saw 105 guide having an upwardly-extending arm provided at the top with corresponding semicircular bearings fitting in those of the hanger or support, whereby the upper band-saw guide is hung from the same, and is capable of a horizontal rotary movement to guide the band-saw before the same enters the material, substantially as described. 110

3. In a device of the class described, the combination of a hanger or support provided with a horizontal arc-shaped bearing arranged concentric with the saw and having a tongue and groove, and an upper band-saw guide having an upwardly-extending arm provided at the top with an arc-shaped bearing portion, the latter having a tongue and groove matching the tongue and groove of the hanger or support, whereby the saw-guide is hung from and located beneath the latter, said band-saw guide being capable of a horizontal rotary 120 movement, substantially as described. 115

4. In a device of the class described, the combination of a hanger or support having 125

upper and lower arc-shaped bearings concentric with the saw, an upper band-saw guide having an upwardly-extending arm provided at the top with corresponding arc-shaped bearings fitting in the said upper and lower bearings, 5

whereby the saw-guide is hung from a hanger or support, and is capable of a horizontal rotary movement to guide the band-saw before the same enters the material, and 10
adjusting means connected with the arm at a point between the upper and lower bearings, substantially as described.

5. In a device of the class described, the combination of a hanger or support provided with 15 upper and lower arc-shaped bearing-plates concentric with the saw and having tongues or grooves, and an upper band-saw guide having an upwardly-extending arm provided at the top with arc-shaped flanges having depending 20 tongues and grooves matching those of the bearing-plates, whereby the saw-guide is hung from the hanger or support, said guide being capable of a horizontal rotary movement, substantially as described.

25 6. In a device of the class described, the combination of a hanger or support provided with a curved portion having vertical flanges, upper and lower arc-shaped bearing-plates having tongues and grooves and provided with flanged 30 portions to fit the flanges of the hanger or support, an upper band-saw guide having an arm or portion provided with arc-shaped flanges having tongues and grooves matching those of the bearing-plates, and a cap extending 35 over the said arm or portion of the band-saw guide, substantially as described.

7. In a device of the class described, the combination of a hanger or support having a curved portion provided with an aperture, said hanger 40 or support being also provided with bearings, an upper band-saw guide mounted in the bearings and capable of a horizontal rotary movement to lead a saw before the same enters the material, ears extending from the band-saw 45 guide and projecting through the aperture of the hanger or support, a block pivotally mounted between the ears, and a threaded adjusting rod or shaft mounted on the hanger or support and connected with the pivoted block, 50 substantially as described.

8. In a device of the class described, the combination of a hanger or support provided with upper and lower curved bearings concentric with the saw, an upper band-saw guide having 55 an arm hung from the bearings and provided

between the same with a projecting portion operating in an opening of the support or hanger, and adjusting means connected with the projecting portion of the arm, substantially as described. 60

9. In a device of the class described, the combination of a hanger or support having a curved portion and provided thereat with upper and lower curved bearings, an upper band-saw guide having a curved portion arranged at the 65 inner face of the curved portion of the hanger or support and hung from the bearings of the same, and provided with a projecting portion extending through an opening of the hanger or support, and a rotary operating rod or 70 shaft journaled on the hanger or support and having a threaded connection with the projecting portion of the band-saw guide, substantially as described.

10. In a device of the class described, the 75 combination of a hanger or support having upper and lower curved bearing-grooves arranged horizontally, a band-saw guide located beneath the hanger or support and having an arm provided with upper and lower depending curved tongues fitting in the said grooves, whereby the band-saw guide is hung from the hanger or support and is capable of a horizontal rotary movement, a cap or plate mounted on the hanger or support and engaging the 85 arm to retain the tongues in the said bearing-grooves, and means for adjusting the hanger, substantially as described.

11. An upper band-saw guide mounted for horizontal rotary movement, the center of 90 which is coincident with the center of the guided portion of the saw.

12. An upper band-saw guide mounted for horizontal rotary movement on an arcuate bearing, which is concentric with the saw. 95

13. An upper band-saw guide mounted for horizontal rotary movement on a semicircular bearing, which is concentric with the saw.

14. An upper band-saw guide mounted for horizontal rotary movement on vertically-spaced arcuate bearings concentric with the saw. 100

In testimony that I claim the foregoing as my own I have hereto affixed my signature in the presence of two witnesses.
